UNITED STATES PATENT OFFICE

122,347

DESIGN FOR A WIND DRIVEN AMUSEMENT DEVICE

George L. Yuran, Kansas City, Kans.

Application October 16, 1939, Serial No. 87,682

Term of patent 7 years

To all whom it may concern:

Be it known that I, George L. Yuran, a citizen of the United States, residing at Kansas City, in the county of Wyandotte and State of Kansas, have invented a new, original, and ornamental Design for a Wind Driven Amusement Device, of which the following is a specification, reference being had to the accompanying drawing, forming a part thereof.

Fig. 1 is a top plan view of the wind driven amusement device; and

Fig. 2 is a side elevational view thereof.

I claim:

The ornamental design for a wind driven amusement device, as shown.

GEORGE L. YURAN.
